UNITED STATES PATENT OFFICE.

LEAL LAMOREAUX AND RALPH J. BOOMER, OF ST. PAUL, MINNESOTA.

ROAD PLANE.

Application filed May 3, 1920. Serial No. 378,539.

To all whom it may concern:

Be it known that we, LEAL LAMOREAUX and RALPH J. BOOMER, citizens of the United States, residing at St. Paul, in the 5 county of Ramsey and State of Minnesota, have invented a new and useful Improvement in Road Planes, of which the following is a specification.

Our invention relates to road planes, the 10 primary object of which is to work the surface of a road true and smooth to accommodate, in the most practical manner, the travel over the same. In this day of development of good roads it is very desirable 15 to have road working mechanism to accomplish certain purposes most effectively in the shortest time, and owing to the extent of traffic of motor vehicles at the present time over practically all roads, a road plane 20 which is adapted to be easily operated is in great demand.

Our road plane is arranged so that the 25 component of forces tending to force rotation about the hitch ring is exactly balanced by one of the blades to cause the plane to run in a straight line. A feature of primary importance in our plane is in means 30 so arranged as to cause the removal of projections in the road coincidental with spreading loose material into the depressions and packing the loose material in the depressions, while a trowelling and finished effect is accomplished by the rear end of the plane. As the projecting portions of the 35 road are cut away by the foremost blade of our plane, the loose material is carried back and spilled around the end of the foremost blade, while a second blade picks up this loose material and spreads it over the 40 surface of the road, tending to fill any depressions and crushing and packing loose material in the depressions, while the third blade of the plane picks up the material spilled around the end of the second blade 45 and acts with the first blade as a cutter, and also tends to pack and distribute any loose material passing along the angle of the blade, while the trowel end of the plane performs to a large degree the effect of a 50 roller or smoothing element to give a finish to the road.

In the drawings forming part of this specification:

Figure 1 is a plan view of our road plane. 55 Figure 2 is a side elevation of the same.

Figure 3 is a detail of an alternative construction of one of the blades.

The drawings illustrate our road plane A, the frame of which is formed with a pair of longitudinally extending beam members 10, 60 which constitute the main supporting portion of the body of the plane A. The forward end of the plane is connected by upper and lower channel members 11 and 12, respectively, which extend transversely across 65 the forward end of the beams 10.

A suitable hitch B is connected to the forward end of the plane A and is provided with connecting rods 13, which converge toward each other and are connected by the 70 hitch ring 14. The ring 14 is connected in any suitable manner, not illustrated, to a tractor or other means for pulling the plane.

The blades of our plane are preferably in the form of channel irons. The forward 75 blade 15 is set obliquely in relation to the forward end of the plane A and rigidly attached in a suitable manner to the beam members 10. The second blade 16 extends obliquely across in the opposite direction to 80 the oblique angle of the blade 15 and is connected to the beam members 10 in a similar manner as the blade 15, while a third blade 17 extends obliquely across the plane A and is secured similarly as the 85 other blades to the beam members 10, extending in an opposite angle to the blade 16. The road surface is worked toward the center of the road by the first blade 15, which is placed at an angle demonstrated to 90 be the most practical for this class of work. The second blade has its end 18 projecting beyond the rear end 19 of the first blade from the side of the plane A to catch the material spilled around the end 18 and 95 carry it along the blade 16 to the other side of the plane A, while the end 20 of the blade 17 projects beyond the end 21 of the blade 16 so that the blade 17 will pick up any material which may be spilled 100 around the end 21 of the blade 16 and tend to carry it along the edge of the blade 17. This construction and arrangement of the blades 15, 16 and 17 tends to carry the loose 105 material picked up by the blades back and forth in a zigzag manner in the direction of the arrows, as illustrated in Figure 1, distributing the loose material to the depressions in the road coincidental with the removal of projections, and packing the 110

- loose material in the depressions by the lower leg 22 of the channel members. The lower leg 22 of the channel members engages flat against the surface of the road.
- 5 The upper legs 23 of each of the channel members contact and are secured to the beam members 10, while suitable braces 24 hold the body of the channel members extending perpendicularly from the lower 10 edge of the beam members 10. The lower forward edge 25 of the channel members 15, 16 and 17 is sufficiently sharp to form a cutting edge for the channels so as to remove projections, while the legs 22 of each 15 of the channels tend to pack any loose material which may slide beneath the same onto the road.

The channels 15 and 17 tend to form the cutters of the plane A and the channel 16 distributes and packs the loose material. The lower edges or legs 22 of each of the blades extend in the same plane, thus insuring a true surface to the road over which the plane is drawn. The effect of the legs 25 22 of the plane in removing and crushing the uneven surface of the road is very effective, and of a material advantage, while the peculiar arrangement of the obliquely set blades so as to carry loose material in a zigzag manner tends to very quickly and effectively true the surface of a road.

The lower sharp edge 25 of the blades may be protected by an adjustable cutting member 26, which is connected by suitable 35 bolts 27 which engage in the slot 28 of the member 26 so that the lower edge 29 of the member 26 can be adjusted to act as a cutting member directly adjacent to the edge 25. This construction is adapted to take up the wear and protect the edge 25 of the blades 15, 16 and 17 if it is desired to use the same on the blades.

A trowelling blade 30 extends transversely across the rear end of the plane and is connected to the rear ends of the beams 10 by suitable braces or brackets 31. The trowelling blade 30 is formed of a channel iron member, the body of which extends at a slight angle in relation to the road, while the outer ends 32 of the blade extend on either side of the plane A, beyond the ends of the blades 15, 16 and 17. The end 34 of the blade 17 may spill a slight amount of material toward the trowel 30 as it is obvious that by the time the material is carried from the blade 15 to the blade 17 most of the loose material will be packed and distributed evenly over and into the depressions in the road, allowing only a small amount of loose material to be carried back to the trowel 30. The trowel or smoother 30 prevents the formation of a shoulder and projects so that it will lap the center of the road and in working material under this blade the surface is packed to the extent 60 65

comparable with the work of a roller. The angle braces 31 can be adjusted to hold the trowel blade 30 in any suitable angle in relation to the road.

Our road plane is to be compared to a 70 certain extent with the laying of a concrete floor, the material of which is struck off with the straight edge, but a trowel is used to finish the surface, because the straight edge leaves the surface porous and uneven. 75 In this same manner the blades of our plane perform the functions of straight edges, while the lower legs 22 of the blades act as trowels to crush and pack the loose material into depressions in the road to give a smooth 80 effect to the same, while the trowel blade puts the finishing touches on the road surface, all with a once-over operation. Therefore, our road plane accomplishes in a short 85 time the effect of a true surface for a road over which it is drawn.

In accordance with the patent statutes we have described the principles of operation of our invention, together with the apparatus which we now consider to represent the best 90 embodiment thereof, but we desire to have it understood that the construction shown is only illustrative and that the invention can be carried out by other means and applied to uses other than those above set forth 95 within the scope of the following claims:

We claim:

1. A road plane including a frame, a number of channel shaped zigzag packing cutters arranged on said frame adapted to discharge from one to the other and a transverse trowel positioned across said frame at the extreme end thereof in transverse relation to said frame, said trowel extending outwardly beyond the ends of all of said zigzag cutter members. 100 105

2. A road plane, comprising a pair of beam members, channel shaped iron blades obliquely and zigzag attached in relation to each other to said beam members with the legs of said angle iron blade members which engage the road extending in the same plane with the road and a trowelling blade fixed rigidly to the rear end of said beam members against movement. 110 115

3. A road plane comprising a frame, a number of channel shaped zigzag packing cutters arranged in inclined relation to one another upon said frame, said blades being arranged with the end of each blade in close proximity to and discharging to the beginning of the succeeding blade and a trowel member secured to the end of said frame, said trowel member being arranged in inclined relation to the ground and of a length to extend on either side of the ends of said zigzag cutters. 120 125

4. A road plane comprising a longitudinally extending frame, a series of channel iron shaped members secured in zigzag man- 130

ner to said frame, to discharge the ground from the first blade to the next succeeding blades, the ground engaging leg of each of said members forming a flat tamping means and an adjustable removable cutting blade secured to each of said members along the cutting edge of the same and a transverse trowel positioned across said frame at the extreme end thereof and extending outwardly beyond the ends of all of said zigzag members.

5. A road plane comprising a longitudinal frame member, a series of channel shaped packing blades supported on said frame member, said blades being arranged in inclined relation to one another with the end

of each blade discharging to the beginning of the succeeding blade and a trowel member secured at right angles to said frame immediately at the rear of said last named 20 succeeding blade adapted to receive the earth discharged therefrom, said trowel member being positioned in inclined relation to the road and having its lowermost edge lying substantially in the same plane as the cutting edges of said cutters, said trowel member extending outwardly beyond the sides of said plane and beyond the ends of all of said cutting members. 25

LEAL LAMOREAUX.
RALPH J. BOOMER.
